VARIABLY DISPLACED REGULATED-VOLTAGE POWER SUPPLY

Robert C. Paulsen, West Caldwell, N. J., assignor to International Business Machines Corporation, New York, N. Y., a corporation of New York

Original application May 26, 1951, Serial No. 228,432, now Patent No. 2,717,994, dated September 13, 1955. Divided and this application February 7, 1952, Serial No. 270,413

5 Claims. (Cl. 323—22)

This invention relates to regulated power supplies, and more particularly to power supplies adapted to provide a regulated voltage which is variably displaced from a given level, as for example ground.

This application is a division of application Serial No. 228,432 filed May 26, 1951, and now Patent 2,717,994 issued September 13, 1955. The parent application relates to measuring and indicating systems and more particularly to improved means for measuring and indicating or manifesting the value of a variable quantity such as an electrical potential or a physical displacement.

A principal object of the present invention is to provide an improved regulated power supply.

Another object of the present invention is to provide a source of regulated voltage which may have a variable displacement with respect to a given level.

In accordance with the present invention, there is provided a regulated power supply which comprises the combination of a plurality of structural elements. These elements include a source of fixed potential having output terminals, plural impedance elements, a voltage-regulating device connected in series with the impedance elements across the fixed source, a source of variable potential having first and second terminals, the first terminal being connected to a first output terminal of the fixed source, means associated with the second terminal for varying the potential drop across a first of the impedance elements as a function of the variable potential, and means for utilizing the potential drop between the second terminal and the junction of a second of the impedance elements and the voltage-regulating device.

Other objects and features of the present invention will be pointed out in the following description and claims and illustrated in the accompanying drawings, which disclose, by way of example, the principle of the invention and the best mode, which has been contemplated, of applying that principle.

In the drawings, in which like reference numerals designate like components:

Fig. 1 is a schematic diagram of a power supply in accordance with the present invention; and

Fig. 2 is a schematic circuit diagram of the comparer unit disclosed in the above-identified parent application and utilizing a power supply in accordance with the present invention.

Referring to Fig. 1, there is shown a regulated power supply in accordance with the present invention comprising a voltage-regulating device 277, preferably comprising a tube of the cold-cathode type. Cathode 278 of tube 277 is connected through a first impedance element or resistor 279 to ground. Anode 280 of tube 277 is connected through a second impedance element or resistor 281 to a terminal 181 of a source of fixed potential (not shown), the other terminal of the potential source being grounded in accordance with conventional practice.

There is provided a source of variable potential having first and second terminals, the first terminal being

2

grounded as shown and the second terminal being designated by reference numeral 244. Means are provided for varying the potential across resistor 279, these means comprising vacuum tube 282, preferably arranged to operate as a cathode follower. Cathode 283 of tube 282 is grounded through resistor 279. Control electrode 284 of tube 282 is connected to terminal 244 to which is applied a variable potential. Anode 286 of tube 282 is connected to terminal 281 of the source of fixed potential. In operation, the potential difference between terminal 244 and anode 280 of tube 277 remains substantially constant in spite of wide variations in the potential of terminal 244 with respect to ground.

By way of example of means for utilizing this advantageous feature of the present invention, there is shown a vacuum tube 239, preferably of the tetrode type. Cathode 240 of tube 239 is grounded through a suitable resistor, control electrode 242 of tube 239 is connected to terminal 244, and screen electrode 297 of tube 239 is connected to the junction of second impedance element or resistor 281 and voltage-regulating device 277. With the arrangement just described, it will be apparent that the potential difference between control electrode 242 and screen electrode 297 of tube 239 will remain substantially constant in spite of wide variations of the potential between control electrode 242 and ground. In this way, therefore, there has been provided in accordance with the present invention a power supply which furnishes a regulated voltage having a variable displacement with respect to a given level, as for example ground.

In order to bring out even more clearly how the advantages of the present invention may be utilized, there is shown in Fig. 2 of the drawings a schematic circuit diagram of the comparer unit disclosed in the above-identified parent application and utilizing a power supply in accordance with the present invention. Referring to this figure, terminal 210, comprising the output terminal of translator unit 14 (Fig. 4 of the above-identified application) is connected through a DPDT switch 235 to a junction 236. Junction 236 is connected through an SPDT switch 237 to anode 238 of an electron discharge device 239 of the pentode type. When switches 235 and 237 are in the positions shown, the comparer unit is adapted to utilize an unknown variable quantity comprising an electrical potential. The system will first be described for operation with this type of unknown input variable.

Cathode 240 of discharge device 239 is grounded through a resistor 241. Control electrode 242 is connected by a switch 243 either to input terminal 244, to which the unknown potential is applied, or to ground. The potential of screen electrode 297 with respect to cathode 240 is maintained substantially constant by an arrangement which will be described later. Suppressor electrode 245 is connected to cathode 240.

It will be apparent that the potential of junction 236 with respect to ground will be dependent upon the potential drop in resistors 194—209 (Fig. 4 of the above-identified parent application) due both to the anode currents of the electron discharge devices of translator unit 14 and to the anode current of electron discharge device 239, as well as to the potential drop across resistor 241 due to the anode current of the latter discharge device. An increase in the anode current of discharge device 239, such as might be caused by applying an input potential between terminal 244 and ground, would tend to decrease the potential between junction 236 and ground. A decrease in the conductivity of one or more of the electron discharge devices of translator unit 14 would tend to cause an increase of potential at junction 236 with respect to ground.

In order to utilize this effect, there is provided a

gaseous discharge device 246 having a cathode 247, a control electrode 248 and an anode 249. Control electrode 248 is connected to junction 236 by a resistor 250. A resistor 251 is connected between positive potential source 181 and anode 249. For the purpose of maintaining substantially constant the anode-cathode potential of discharge device 246 so that it will fire at fixed control-electrode potential, there is provided a series network comprising a resistor 252 and an electron discharge device 253, preferably of the pentode type and having a cathode 254 which is grounded through a resistor 255. A resistor 256 is connected between cathode 247 of discharge device 246 and anode 257 of discharge device 253. Control electrode 258 of device 253 is grounded. Screen electrode 259 is connected through an adjustable resistor 260 to positive potential source 35, suitable additional resistors 261 and 262 being provided and arranged as shown. Suppressor electrode 263 is connected to cathode 247.

In operation, assuming first that counter unit 13 (Fig. 3 of the above-identified parent application) is set at 0000 and that switch 243 is in its right-hand position, resistor 260 is adjusted so that gaseous device 246 is barely extinguished. In other words, a small increase in the potential of junction 236 with respect to ground would cause discharge device 246 to fire, with the result that a large positive-going pulse is developed at cathode 247.

Now let it be assumed that switch 243 is in its left-hand position and that an unknown potential has been applied to input terminal 244. This causes the potential of junction 236 to decrease with respect to ground, so that control electrode 248 of discharge device 246 becomes more negative with respect to cathode 247. As previously described, however, counter unit 13 has begun counting, so that the potential drop across resistors 194—209 (Fig. 4 of the above-identified parent application) gradually decreases until the potential of junction 236 with respect to ground rises sufficiently to cause discharge device 246 to fire. The resultant positive-going pulse at cathode 247 is applied by means of a capacitor 264 to control electrode 265 of an electron discharge device 266, operating as a cathode follower and having its cathode 267 coupled by means of a capacitor 268 to lead 65. The resultant positive-going pulse developed across cathode resistor 269 causes the closing of gate unit 11, as previously described in connection with Fig. 2, thus terminating the first portion of a complete operating cycle.

For the purpose of extinguishing discharge device 246 very shortly after it fires, there is provided an electron discharge device 270 having a cathode 271 connected to positive potential source 35. Control electrode 272 of device 270 is connected through a resistor 273 and lead 274 to junction 60 in gate trigger circuit 49 (Fig. 2 of the above-identified parent application). Control electrode 272 is bypassed to ground by a capacitor 275. Anode 276 of device 270 is connected to anode 249 of discharge device 246. When trigger circuit 49 is on during the measuring portion of each cycle, the left-hand portion of discharge device 50 (Fig. 2 of the above-identified parent application) is non-conductive and the potential of junction 60 is such that control electrode 272 is substantially negative with respect to cathode 271 of discharge device 270, so that this device is non-conductive. Upon the firing of discharge device 246, trigger circuit 49 is turned off, the left-hand portion of discharge device 50 becoming conductive and the potential of junction 60 increasing sufficiently to render discharge device 270 highly conductive. The resultant additional current flow through resistor 251 causes the potential of anode 249 of discharge device 246 to fall below that of cathode 247, thereby extinguishing this discharge device. This con-

dition is maintained until the measuring portion of the succeeding complete cycle is initiated.

In order that the anode current of discharge device 239 shall vary linearly with respect to changes in the unknown potential applied to terminal 244 and hence to its control electrode 242, it is necessary that the potential of screen electrode 297 remain substantially constant with respect to that of cathode 240 of discharge device 239. For the purpose of accomplishing this, there is provided a voltage regulator tube 277, preferably of the cold-cathode type, having its cathode 278 connected through an impedance element or resistor 279 to ground, and having its anode 280 connected through an impedance element or resistor 281 to positive potential source 181. Screen electrode 297 of discharge device 239 is connected to anode 280 of regulator tube 277. There is also provided an electron discharge device 282, preferably of the tetrode type and having its cathode 283 connected to cathode 278 of regulator tube 277. Control electrode 284 of discharge device 282 is connected to control electrode 242 of discharge device 239. Screen electrode 285 and anode 286 of discharge device 282 are connected together and to positive potential source 181. Since discharge device 282 operates as a cathode follower, variations in the potential of its control electrode 284 due to changes in the unknown potential applied to input terminal 244 are reflected linearly in the potential drop existing across resistor 279 due to the anode current of discharge device 282. Thus the potential of cathode 283 varies directly as does that of cathode 240 of discharge device 239. Because of the action of voltage regulator tube 277, its anode 280 remains at a substantially constant potential above that of its cathode 278, with the result that the difference in potential between screen electrode 297 and cathode 240 of discharge device 239 remains substantially constant, irrespective of the magnitude of the unknown potential applied between input terminal 244 and ground. The provision of this arrangement for securing a linear relationship between the unknown potential applied to terminal 244 and the anode current of discharge device 239 constitutes an important feature of the present invention.

While there have been shown and described and pointed out the fundamental novel features of the invention as applied to a preferred embodiment, it will be understood that various omissions and substitutions and changes in the form and details of the device illustrated and in its operation may be made by those skilled in the art, without departing from the spirit of the invention. It is the intention, therefore, to be limited only as indicated by the scope of the following claims.

What is claimed is:

1. In combination: a source of fixed potential having output terminals; plural impedance elements; a voltage-regulating device connected in series with said impedance elements across said fixed source; a source of variable potential having first and second terminals, said first terminal being connected to a first output terminal of said fixed source; means associated with said second terminal for varying the potential drop across a first of said impedance elements as a function of said variable potential; and means for utilizing the potential drop between said second terminal and the junction of a second of said impedance elements and said voltage-regulating device.

2. In combination: a source of fixed potential having output terminals; plural impedance elements; a voltage-regulating device connected in series with said impedance elements across said fixed source; a source of variable potential having first and second terminals, said first terminal being connected to a first output terminal of said fixed source; means associated with said second terminal for varying the potential drop across a first of said impedance elements linearly as a function of said variable potential; and means for utilizing the potential

drop between said second terminal and the junction of a second of said impedance elements and said voltage-regulating device.

3. In combination: a source of fixed potential having output terminals; plural impedance elements; a voltage-regulating device connected in series with said impedance elements across said fixed source; a source of variable potential having first and second terminals, said first terminal being connected to a first output terminal of said fixed source; means associated with said second terminal for varying the potential drop across a first of said impedance elements as a function of said variable potential, said means comprising a cathode follower utilizing said first impedance element as its load impedance; and means for utilizing the potential drop between said second terminal and the junction of a second of said impedance elements and said voltage-regulating device.

4. In combination: a source of fixed potential having output terminals; plural impedance elements; a voltage-regulating device connected in series with said impedance elements across said fixed source, said device comprising a tube of the cold-cathode type; a source of variable potential having first and second terminals, said first terminal being connected to a first output terminal of said fixed source; means associated with said second terminal for varying the potential drop across a first of said impedance elements as a function of said variable po-

10

15

tential; and means for utilizing the potential drop between said second terminal and the junction of a second of said impedance elements and said voltage-regulating device.

5. In combination: a source of fixed potential having output terminals; plural impedance elements; a voltage-regulating device connected in series with said impedance elements across said fixed source, said device comprising a tube of the cold-cathode type; a source of variable potential having first and second terminals, said first terminal being connected to a first output terminal of said fixed source; means associated with said second terminal for varying the potential drop across a first of said impedance elements linearly as a function of said variable potential, said means comprising a cathode follower utilizing said first impedance element as its load impedance; and means for utilizing the potential drop between said second terminal and the junction of a second of said impedance elements and said voltage-regulating device.
